(57) **CLAIM**

The ornamental design for a removable battery, as shown and described.

DESCRIPTION

FIG. 1 is a perspective view of a removable battery according to one embodiment of the present invention;

FIG. 2 is a bottom view of the removable battery shown in FIG. 1;

FIG. 3 is a right side elevation view of the removable battery shown in FIG. 1;

FIG. 4 is a left side elevation view of the removable battery shown in FIG. 1;

FIG. 5 is a front elevation view of the removable battery shown in FIG. 1;

FIG. 6 is a rear elevation view of the removable battery shown in FIG. 1; and,

FIG. 7 is a top view of the removable battery shown in FIG. 1.

The broken lines shown herein are for illustrative purposes only and form no part of the claimed design.
